ENGINE, PROPELLER, AND FAN DRIVE

Pierre Ernest Mercier, New York, N. Y.

Application December 13, 1941, Serial No. 422,823

14 Claims. (Cl. 244—53)

1

This invention has reference to aircraft. The drag of a wing or a nacelle subjected to the slipstream of a tractor propeller is known to increase directly with the velocity of the slipstream and is known to change the efficiency of the propeller. It is also commonly known that when the propeller is placed behind the wing and operates as a pusher propeller (and not as a tractor) loss of efficiency is due to the fact that the screening effect of the nacelle and the wing disturb the operation of said propeller. In either case the loss of efficiency of the propeller will be localized mainly in the neighborhood of the nacelle and near the axis of rotation of the propeller.

The present invention has for its principal object arrangements resulting in the elimination of the greater part of the above drawbacks. The invention is in principle applicable to aircraft propelled by tractor as well as pusher propellers, but is of particular interest in the case of pusher propellers. It consists essentially of the association of a propeller and a member of the turbine or fan type, preferably arranged to rotate on one and the same axis, said members being driven at different speeds, the turbine turning from 2 to 5 times more rapidly than the propeller and preferably in an opposite direction, and the turbine being so related to the propeller as to bring about a smooth flow of air axially of the central portion of the area defined by the rotating propeller and rearwardly of the direction of travel of the aircraft, so that, in the case of a tractor propelled aircraft, the slipstream effect is reduced, and, more particularly in the case of an aircraft driven by a pusher type propeller, so that the screening effect of the nacelle and turbulence of the boundary layer of air will be minimized and the efficiency of the propeller increased.

According to one advantageous embodiment of the invention, the turbine is arranged in an annular fairing concentric with the spinner of the propeller or with a fairing which extends about the propeller shaft and the turbine drive gearing, either intermediate the propeller shaft and the spinner or from the propeller toward the engine, and which continues the streamlined contour of the spinner. The annular fairing, depending on whether the turbine is in the front or rear of the propeller, is carried by the nacelle or supported from the mounting for the shaft driving the propeller or transmitting to it the motor torque. The annular fairing may be limited in a longitudinal direction to the zone of action of the fixed or movable vanes of the turbine, or may be a fixed fairing of greater length.

2

The concentrically arranged fairings in effect define a generally annular passage open at both ends through which air is drawn by the action of the turbine for the purposes hereinafter more fully detailed. This annular passage is advantageously arranged in communication at its forward end with an intake orifice or slot extending annularly about the nacelle at a point in its length rearward of its greatest diameter and through which air from a boundary layer is sucked into the annular passage by the action of the turbine and discharged therefrom through an annular discharge outlet or nozzle defined between the concentrically arranged fairings at the rear end of the annular passage. This discharge nozzle is preferably somewhat constricted as compared with the cross-section of the annular passage toward its forward end. This constriction may be brought about by appropriately tapering the annular fairing so that it is frustoconical in shape and presents an outer contour generally conforming to the streamlined shape of the nacelle.

The annular passage may also receive air that has been led within the nacelle through an inlet orifice or orifices other than that mentioned above and which has been utilized for cooling the engine or operating elements thereof.

According to still another modification, the annular passage may merely open forward to receive air from the boundary layer traveling along the nacelle surfaces, in which case the sucking action of the turbine will accelerate flow of the boundary air along the nacelle without first drawing it through slots or orifices in the nacelle fairing.

A further feature of the invention resides in the arrangements for driving the propeller and the turbine from the same power source through differential gearing which insures that the power delivered by the motor or engine is divided in a ratio related to the speeds of rotation of the driven members with respect to that of the motor shaft. In one embodiment of the invention, for example, the number of revolutions of each of the two driven members is related to the running speed of the engine by a simple ratio so that as the speed of the propeller is increased or decreased relative to the engine speed the speed of the fan is decreased or increased, as the case may be, relative to the engine speed. By varying the pitch of the propeller, and therefore its speed, the speed of rotation of the turbine may be varied for one and the same engine speed.

A considerable advantage obtained from this arrangement is that the turbine may be operated

at a higher speed as the speed of the aircraft is increased during normal flight with a corresponding decrease in the R. P. M. of the propeller. This is precisely what is desirable from the point of view of improving the propulsive efficiency; for the greater the speed of translation the more the circumferential speed of the propeller blade may be reduced to increase efficiency. At the same time the differential gearing arrangements permit the propeller to be "revved" up to a high speed and operated at a high R. P. M., and, if desired, with an increased pitch, during take-off and in climbing operations. Under these conditions, speed of translation is relatively low and the problems that the turbine is desired to overcome are not presented to a marked degree. Consequently, the speeding up of the propeller may be, and preferably is, accompanied by a decrease in the speed of the turbine. The differential gearing arrangements of the present invention automatically insure this flexibility of operating conditions and the efficient utilization of the power output of the engine under the above-mentioned varying conditions of aircraft operation.

According to one particularly simple embodiment of the invention, the predetermined division of the power input is obtained by means of a combination of gear wheels including a ring gear of relatively large diameter with internal teeth arranged in concentric relation to a relatively small sun gear and operatively connected thereto by intermediate planetary gears. In this embodiment of the invention the motive power is applied to the ring gear and the propeller is driven by the ring gear through the intermediate or planetary gears which are mounted on a carrier that is either fixed to or operatively connected for driving the propeller. The turbine is driven in direct relation to the rotation of the central pinion or sun gear which latter is driven through the intermediate or planetary gears by the ring gear. This arrangement insures a division of the power input in a predetermined fixed ratio between the propeller and the turbine, and also insures that variations in the speed of the propeller will be accompanied by inverse variations in the speed of the turbine. The ratios of the several gears—the ring gear, the planetary gears, and the central sun gear—are so chosen as to insure that throughout the contemplated operating range of propeller speeds, the turbine will have a speed of from two to five times that of the propeller.

In accordance with an optional modification of the invention it is possible to apply all the motive power to the propeller operating alone during the take-off, the turbine being stopped. This is accomplished by a locking or braking means for immobilizing the central pinion connected to the turbine, in which case all of the power applied to the ring gear is utilized in driving the planetary gears through their path of revolution about the central pinion, and these in turn transmit the available power to the propeller to the exclusion of the turbine.

In a further modified arrangement such locking or braking means may be provided for immobilizing the propeller, as for example in high altitude level flight, whereupon all the power input may be applied in driving the turbine under these particular flight conditions. Such a condition of operation makes for rapid and economical flight, particularly in the operation of multi-

engine aircraft or aircraft provided both with propellers and auxiliary propulsive means.

According to still another embodiment of the invention, the turbine may be replaced by a wheel carrying numerous radially extending vanes or blades appropriately curved and arranged to function similarly as a ventilating fan. In this embodiment the fan may advantageously be mounted for rotation about the propeller axis with the blades projecting radially through an annular slot in the spinner portion of the propeller assembly at the rear of the propeller.

If the fan or turbine is arranged between the differential gearing and the propeller, the differential gearing is advantageously enclosed by a fairing forming an extension of the streamlined contour of the spinner, and the concentrically spaced annular auxiliary fairing may be centered with respect to the fairing surrounding the casing for the differential gearing by means of streamlined bracing wires or streamlined piano wires, in this way reducing drag on the air drawn by the turbine through the annular passage therebetween. When the turbine is arranged to the rear of the propeller, in the case of a pusher propeller, the differential gearing may be supported by the overhanging end of the propeller shaft, and its casing may rotate with and carry the intermediate or planetary gears.

The invention will now be described more fully with reference to the accompanying drawings by way of example. In said drawings:

Figure 1 is a part vertical longitudinal section and part elevation of an application of the invention to a propulsive nacelle provided with a liquid cooled engine.

Figure 2 is a vertical section on a larger scale of an arrangement of a turbine, differential reducing gearing and propeller drive according to the invention, the turbine and the propeller being on the same side of the reduction gearing, the propeller being disposed in the rear of the turbine at the rear of the nacelle or of the fuselage, as the case may be.

Figure 3 is an axial section of a reducing gearing according to the invention, the casing of which rotates with the propeller, and in which the turbine and propeller are arranged at opposite sides of the reducing gear, the turbine being in the rear of the propeller with relation to the support of the drive shaft.

Figure 4 is a partially developed cylindrical section on the line A—A of Fig. 3 showing the section of the vanes of the turbine and its straightening vanes carried by a flange integral with the drive shaft.

Figure 5 is a vertical section of still another modification of the invention in which the reduction gearing and the fan are disposed on opposite sides of the propeller.

Figure 6 is a view partly in vertical section and partly in side elevation showing an engine nacelle with the propeller arrangement applied thereto.

Referring to Figure 1 the fairing of the engine nacelle is shown at 1. It presents in front an axially arranged opening 2 communicating by means of the pipe 3 with the air intake of the engine 4. Machine guns or cannon 5 are arranged in front of the engine in the case of a military airplane.

The wing profile on which the engine-nacelle is mounted is seen at 6. The pipes carrying the cooling liquid of the engine are shown at 7 and 8. These pipes lead to radiator members such as 9 and 10. Slots 11 and 12 disposed in the rear

of the maximum cross section of the nacelle of the engine admit of the drawing-in of the boundary layer, the air entering through slots 11 passing through the radiators 9 and 10 and then passing with the air entering through the slots 12 to and through the turbine.

The casing of the reduction gearing associated with the propeller and the turbine is seen at 13. It is supported by the frame 14. The motive power is conveyed by the transmission shaft 15. The annular fairing 16 surrounds the turbine 17a, which carries vanes 17. Piano wires 18 center the fairing 16 with respect to the central body 19, and streamlined fairings 20 enclose the piano wires 18.

One of the blades of the propulsive propeller is shown at 21, its spinner at 22.

Referring to Figure 2, we find again in Figure 2 the vanes 17 of the turbine the wheel of which is seen at 23. Straightening vanes 24 are carried by the annular fairing 16. A propeller blade is seen at 25, its cuff at 26. The spinner 22 of the propeller is provided with an internal flange 27. The propeller hub 28 is locked on the cone 29 which forms the end of the shaft 30. The latter is centered on the opposite side of the propeller by means of the bearing 31 carried by the member 32, which receives the motor couple by means of the coupling 33 which is integral in rotation with the end of the transmission shaft 15. The member 32 is carried by the bearing 34 mounted in the front plate 35 of the casing 13. The plate 35 is provided with lugs 36 for attachment. The member 32 supports the ring gear 37. Intermediate gears 38 mesh with the gear 37, the stub shafts 39 of these gears being supported by the intermediate gear carrier 40 keyed to the propeller shaft 30. The intermediate gears 38 actuate the central pinion 41, which is integral with the wheel 23 of the turbine. These members are centered on the shaft 30 by means of the bearings 42 and 43, and supported in the casing by the bearing 44.

At 45 and 46 there is shown diagrammatically a pawl and ratchet wheel between the wheel 23 and the casing, which is provided for the purpose of immobilizing the wheel 23 during the take-off. A control (not shown) may release the wheel 23 at the desired moment when the aircraft is in normal flight. It is clear that a brake or equivalent member of a conventional type would serve the same purpose. A similar braking or locking arrangement may be provided to hold the propeller against rotation under certain flight conditions so as to rely solely upon the fan or turbine for propulsion.

Referring now to Figure 3 the axis of the device is marked 47-47. 48 is the drive shaft. It is supported by a bearing or system of bearings occupying the place of the reduction gears 39 in the case of Figure 1.

The shaft 48 has an internal recess 50 and an axial pipe 51. The pipe conveys lubricating oil under pressure through passages such as 52 to the space 54 and the bearings for the gears disposed therein. The oil is returned through passages such as 53 to the recess 50 after one or several oil pumps (not shown) have forced it into the space 54. The propeller hub is seen at 55, the root of a blade at 56, its cuff at 57.

The propeller hub is carried by a member 58, centered on the shaft 48 by means of bearings 59 and 60. The member 58 plays the part of a plate closing the casing 61. The stub shafts 62 of the intermediate gears 63 are fixed in the member 61.

The intermediate gears mesh outwardly with the internal ring gear 64 carried by the member 65 which is keyed to the shaft 48. The intermediate gears mesh inwardly with the central pinion 66, which is guided on the shaft 48 by the bearings 67 and 68. The pinion 66 is integral with the turbine wheel 69, which carries the vanes 70. The vanes 70 move in the interior of the annular fairing 71, which through the vanes 72 is integral with the flange 73 keyed to the shaft 48. This shaft also carries the flange 74, secured by the nut 75 which centers the nosepiece 76.

The external fairing of the rear portion of the nacelle is seen at 77, its interior surface at 78; it defines an annular passage for removing the cooling air circulating in the nacelle.

Figure 5 shows an embodiment of the invention in which the casing for the reduction gearing is fixed and arranged in advance of the propeller and on the opposite side thereof with respect to the turbine wheel or fan associated with these two elements. In the case of this figure, the turbine is replaced by a wheel carrying numerous vanes like a ventilating fan. This embodiment is moreover characterized by the feature that this wheel turns at the end of the propeller shaft and is driven by the central pinion by means of a torque rod or tube, concentric with the propeller shaft and arranged inside the latter in an appropriate bore.

In Figure 5, like members as shown in previous figures are identified by corresponding reference numerals. 56 is a propeller blade, 57 its cuff, 28 the propeller hub. The pitch changing mechanism is shown diagrammatically at 81. It is provided with an insulating disc 82 carrying the usual current supply rings. (The pitch changing mechanism shown is of the electric control type.) The carbon brush-carrying block customarily associated with the rings of the disc 82 is seen at 83. The fan or turbine wheel is provided with vanes such as 84 which are secured in place by flange members 85 and 86. The members 85 and 86 are secured together for rotation on the end 87 of the propeller shaft, being supported in bearings 88 and 89. The fan assembly thus formed is caused to rotate by means of the grooves 91 arranged in the member 86 and carried by the outside of the torque rod 93. A plug 92 tightly closes the central opening in the member 86.

The spinner 76 is centered on the member 86 by means of a partition in the shape of a truncated cone 74. A labyrinth joint 90 prevents the leakage of oil between the member 85 and the propeller shaft. The propeller hub 28 is secured to the propeller shaft 94 by means of the conventional spline and groove connection shown at 94a.

The shaft 94 is provided with oil return passages such as 95. It is supported in the nose of the reduction gearing casing 101 by bearings 96 and 97. This shaft 94 is part of the support 40 for the stub shafts 39 carrying the intermediate gears 38.

The internal ring gear 37 is supported by two plates 100 and 103 with a peripheral flange portion thereof held between opposed flanges carried by the plates. The plate 100 is centered on and supported by the member 94 by means of the bearing 98. The other, 103, is in one piece with the shaft 32 to which the motive force is applied. The central pinion 41 is centered by means of the bearings 99 and 104. It is integral in rotation with the torque rod 93.

If desired, a slip coupling may be inserted be-

tween the torque rod 93 and the central pinion 41 or between the said torque rod 93 and the member 86.

The housing for the reduction gearing is supported by tubular struts such as 14, some being attached to the plate 35 by means of bolts 36, the others being fixed to the case 101 by means of bolts 102.

In Figure 6, 1 is the engine nacelle, containing the engine 4 and its radiators 9 and 10, connected to the engine by the pipes 7 and 8. The transmission shaft 15 links the engine 4 to the mechanism shown on a larger scale in Figure 5 and enclosed in the outer fairing 105. An air intake is arranged in front of the nacelle at 109. It feeds through the passage 108 to the radiators by means of branched conduits shown schematically at 107 and arranged in the rear of the engine 4. An annular slot is arranged between the fairing 105 and the rear edge of the fairing of the nacelle 1, which latter is provided with flaps 106 that allow for varying the slot according to flight conditions.

The fixed fairing 105 is extended by means of the movable fairing 79 of the propeller hub and by the spinner 76 associated with the fan wheel or turbine.

While the invention has been more particularly described in association with a pusher-type propeller, it will be understood that it may equally be employed with a tractor-type propeller in which case the fan or turbine may be employed secondarily to supply compressed air to the engine, the fan or turbine serving as the active member of a supercharger for example, or the fan or turbine may deliver the air to a rear propulsive nozzle, or part of the air may be delivered to the supercharger and part to a rear propulsive nozzle as desired.

Having now fully described my invention, I claim:

1. In an aircraft propulsion system including an engine, a nacelle and a pusher type propeller mounted adjacent the rear of the nacelle to rotate upon the axis of said nacelle, in combination, a fan rotatable upon the same axis as the propeller and arranged to direct flow of air from the boundary layer about the nacelle rearwardly adjacent the hub of the propeller, and a differential driving connection between said engine and said propeller and between said engine and said fan adapted to vary the speeds of the propeller and of the fan inversely with respect to each other upon the occurrence of differential rotation of either the propeller or the fan with respect to the rotation of the engine drive shaft.

2. In an aircraft propulsion system including an engine, a nacelle, and a propeller rotatably mounted adjacent said nacelle, in combination, a fan arranged to direct flow of air from the boundary layer about the nacelle rearwardly thereof and about the axis of the propeller, and a differential driving connection between said engine and said propeller and between said engine and said fan adapted to vary the speeds of the propeller and of the fan inversely with respect to each other upon the occurrence of differential rotation of either the propeller or the fan with respect to the rotation of the engine.

3. In an aircraft propulsion system including an engine, a nacelle enclosing the engine, and a pusher type propeller located adjacent the rear of the nacelle, in combination, a fan mounted to be rotatable about the same axis as the propeller and arranged to direct flow of the boundary layer

of air about the nacelle rearwardly adjacent the hub of the propeller, a driving connection between said engine and said propeller, means for driving the fan at a speed sufficient substantially to reduce the drag of the boundary layer of air on the nacelle in the vicinity of the propeller, and including means operatively connected between said propeller driving connection and said fan driving means for varying the speeds of the propeller and of the fan inversely with respect to each other in response to occurrence of differential rotation of either the propeller or the fan with respect to the rotating speed of the engine drive shaft.

4. In an aircraft propulsion system including an engine, a nacelle enclosing the engine, and a pusher type propeller located adjacent the rear of the nacelle, in combination, a fan mounted to be rotatable about the same axis as the propeller and arranged to direct flow of the boundary layer of air about the nacelle rearwardly adjacent the hub of the propeller, a driving connection between said engine and said propeller, means for driving the fan in a direction opposite to that in which the propeller is driven and at a speed sufficient substantially to reduce the drag of the boundary layer of air on the nacelle in the vicinity of the propeller, and including means operatively connected between said propeller driving connection and said fan driving means for varying the speeds of the propeller and of the fan inversely with respect to each other upon occurrence of differential rotation of either the propeller or the fan with respect to the rotating speed of the engine drive shaft.

5. In an aircraft propulsion system including an engine and a nacelle enclosing the engine, in combination, a pusher type propeller located adjacent the rear of the nacelle, a fan arranged to direct flow of air from the boundary layer of air about the nacelle rearwardly adjacent the hub of the propeller, a shaft driven by said engine, a chain of gearing driven by said shaft for driving said propeller and said fan and including differential gearing between said shaft and said propeller and between said shaft and said fan adapted to vary the speeds of the propeller and of the fan inversely with respect to each other whenever the speed of one or the other varies relative to the speed of said shaft.

6. In an aircraft propulsion system including an engine and a nacelle enclosing the engine, in combination, a pusher type propeller located adjacent the rear of the nacelle, a fan arranged to direct flow of air from the boundary layer of air about the nacelle rearwardly adjacent the hub of the propeller, a shaft driven by said engine, a chain of gearing driven by said shaft and including a large internal ring gear driven from said shaft, an intermediate planetary gear meshing therewith, and a central pinion meshing with said planetary gear, said fan being connected with and driven by said central pinion, and said propeller being connected with and driven by said planetary gear, so that the torque applied to the propeller and to the said fan is in a fixed ratio.

7. In an aircraft propulsion system including an engine, a nacelle enclosing the engine, and a pusher type propeller located adjacent the rear of the nacelle and driven by said engine, in combination, a fan rotatable around the same axis as the propeller and arranged to direct air rearwardly from the nacelle adjacent the hub of the propeller, and means driving said fan at a speed

at least twice that of the propeller, said means including a large internal ring gear driven from said shaft, an intermediate gear meshing therewith, and a central pinion meshing with said intermediate gear, said fan being connected with and driven by said central pinion, and said propeller being connected with and driven by said intermediate gear, so that the torque applied to the propeller and to the said fan is in a fixed ratio.

8. In an aircraft propulsion system including an engine and a nacelle enclosing the engine and a pusher type propeller located adjacent the rear of the nacelle and driven by the engine, in combination, a fan mounted rearwardly of and adjacent the propeller and rotatable about the same axis as the propeller, said fan being further so arranged as to induce flow of air rearwardly adjacent the hub of the propeller, and means for driving the fan at a speed at least twice that of the propeller during normal flight operation, thereby to reduce turbulence in and drag of the boundary layer of air on the nacelle in the vicinity of the propeller, said means for driving the fan including a differential driving connection between said fan and said propeller and between said propeller and said engine adapted to vary the speeds of the propeller and of the fan inversely with respect to each other whenever the speed of one or the other varies relative to the speed of the engine.

9. In an aircraft propulsion system including an engine, a nacelle enclosing the engine, and a pusher type propeller driven by said engine and located adjacent the rear of said nacelle, in combination, a fan rotatable around the same axis as the propeller and arranged to direct air rearwardly from the nacelle adjacent the hub of the propeller, and means driving said fan by means of a torsion rod concentric with and located within the engine drive shaft at a speed at least twice that of the propeller, said means including a large internal ring gear driven from said shaft, an intermediate gear meshing therewith, and a central pinion meshing with said intermediate gear, said fan being connected with and driven by said central pinion, and said propeller being connected with and driven by said intermediate gear, so that the torque applied to the propeller and to the said fan is in a fixed ratio.

10. An aircraft as claimed in claim 3 wherein the said fan is arranged between the engine and the propeller.

11. In an aircraft propulsion system including a liquid-cooled engine and radiators therefor, means for admitting external air to cool said radiators, and a propeller, in combination, a turbine-type fan rotatable around the same axis as the propeller and located between said radiators and said propeller with its peripheral portions located in the path of movement of the said admitted external air, and means for driving said fan at a speed at least twice that of said propeller to direct the air passing said radiators rearwardly adjacent the axis of said propeller at a sufficient speed to substantially eliminate drag of the boundary layer of air on the nacelle in the vicinity of said propeller, said means including a differential driving connection between said engine and said propeller and between said engine and said fan adapted to vary the speeds of the propeller and of the fan inversely with respect to each other upon the occurrence of differential rotation of either the propeller or the fan with respect to the rotation of said engine.

12. In an aircraft propulsion system including an engine, a nacelle enclosing the engine, and a pusher type variable pitch propeller located adjacent the rear of the nacelle, in combination, a fan rotatable upon the same axis as the propeller and arranged to direct air from the boundary layer adjacent the nacelle rearwardly adjacent the axis of the propeller, a driving connection between said engine and said propeller and between said engine and said fan, said connection including a differential driving mechanism adapted upon variation of the propeller speed effected by varying the pitch of the propeller to inversely vary the speed of the fan with respect to the propeller speed while said engine speed is maintained substantially constant.

13. In an aircraft propulsion system including an engine, a nacelle enclosing the engine, and a pusher type propeller located adjacent the rear of the nacelle, in combination, a fan rotatable around the same axis as the propeller and arranged to direct air rearwardly from the nacelle adjacent the hub of the propeller, a driving connection between said engine and said propeller and between said engine and said fan which includes a differential driving mechanism adapted to drive the propeller at increased speed upon reduction of the speed of the fan when operating at a given engine speed, and means for locking said fan against movement so that all the power of the engine drive shaft may be applied to said propeller, as during take-off.

14. In an aircraft propulsion system including an engine, a nacelle enclosing the engine, and a pusher type propeller located adjacent the rear of the nacelle, in combination, a fan rotatable around the same axis as the propeller and arranged to direct air rearwardly from the nacelle adjacent the hub of the propeller, a driving connection between said engine and said propeller and between said engine and said fan for driving said fan at a speed sufficient to substantially reduce turbulence in and drag of the boundary layer of the air in the vicinity of the propeller, said driving connection including a differential driving mechanism acting upon reduction of the propeller speed to increase the speed of the fan for a given engine speed, and means for locking the said propeller against movement so that all of the power of said engine shaft may be applied to said fan under desired flight conditions.
